UNITED STATES PATENT OFFICE.

FREDRICK SCHLUETER AND CLARENCE MERICLE, OF DETROIT, MICHIGAN.

CARBURETER.

1,213,028.

Specification of Letters Patent. Patented Jan. 16, 1917.

Application filed February 9, 1916. Serial No. 77,223.

To all whom it may concern:

Be it known that we, FREDRICK SCHLUETER and CLARENCE MERICLE, citizens of the United States, residing at Detroit, in the 5 county of Wayne and State of Michigan, have invented new and useful Improvements in Carbureters, of which the following is a specification.

This invention relates to carbureters, the 10 chief aim of the invention being to produce a carbureter the construction and operation of which will eliminate the danger of back fire from the engine which so frequently results in setting fire to the carbureter and 15 the fuel which has escaped therefrom by reason of the intentional or unintentional flooding of the carbureter preparatory to starting the engine in operation.

More specifically stated, the object of the 20 present invention is to produce a carbureter in which the air and fuel chambers are separated in such a manner as to prevent the flame in case of back fire from entering the bowl or chamber in which the fuel is 25 contained, the construction hereinafter described eliminating the volume of air rushing in ahead of the fuel on quick acceleration and which causes a lean mixture; the construction also providing for relieving 30 the pressure on the air valve in such event.

With the above and other objects in view, the invention consists in the novel construction, combination and arrangement of parts, as herein described, illustrated and claimed.

35 In the accompanying drawings:—Figure 1 is a front elevation of a carbureter embodying the present invention. Fig. 2 is a side elevation of the same. Fig. 3 is a vertical longitudinal section on the line 3—3 of Fig. 1. Fig. 4 is a vertical section on the line 4—4 of Fig. 2. Fig. 5 is a horizontal section on the line 5—5 of Fig. 2. Fig. 6 is a vertical section on the line 6—6 of Fig. 4. Fig. 7 is a vertical longitudinal 40 section through the air chamber and the lower portion of the mixing chamber. Fig. 8 is a bottom plan view of the air chamber. Fig. 9 is a vertical section on the line 9—9 of Fig. 7. Fig. 10 is a vertical section on the line 10—10 of Fig. 7. Fig. 11 is a top plan view of the air chamber showing the combined relief valve and gate. Fig. 12 is a detail view of the auxiliary air inlet valve.

50 The carbureter contemplated in this invention comprises the three main elements

or sections A, B and C, A representing the carbureting chamber, B the bowl which contains the fuel oil and C the air chamber.

The carbureting chamber A is shown in 60 form of a tubular body or pipe which is provided at the top thereof with the usual flange 1 by means of which the carbureter as a whole is fastened to a corresponding flange of the intake pipe or manifold of 65 an internal combustion engine in a manner well understood by those familiar with the art to which this invention appertains. Located within said tubular body or pipe A is a throttle valve 2 of the butterfly type, 70 the same being provided with the usual stem 3 journaled in bearings in the pipe A and provided exteriorly thereof with an operating lever 4 controlled by means of the usual connections from the dash of a 75 motor vehicle.

The pipe A is provided at a suitable elevation with laterally and oppositely extending flanges 5 bearing a tangential relation to the exterior surface of said pipe and having their outer faces machined to provide a flat face 6 against which the similarly machined flat face 7 of the bowl B is fastened by means of cap screws 8 or their equivalent. The pipe forming the mixing 85 chamber A is also formed with an orifice 9 in the flat face 6 thereof to receive a tubular elbow 10 forming the fuel outlet of the bowl B. The upstanding end of the elbow 10 is threaded to receive a nozzle or jet 11 90 which is threaded tightly thereon as shown, the exit opening of said nozzle or jet being of any desired size in accordance with the capacity and requirements of the engine. It is intended to employ a number of in- 95 terchangeable nozzles or jets 11 of different lengths and capacities so that the exit opening of the jet or nozzle will be located about one-half of an inch, more or less, above the normal level of fuel in the bowl B. 100 The nozzle or jet 11 extends upwardly and is located centrally within the mixing chamber A.

The bowl B is provided with a fuel inlet 105 nipple 12 to which the usual fuel feed pipe is connected and within said nipple is arranged a fuel inlet valve 13 having a tapered valve face 14 and a reduced stem 15 extending into the bowl B as shown in Fig. 4 where it is adapted to come in contact with the depending arm 16 of an elbow lever 17 which is pivotally mounted at 18 within

the bowl, the lever 17 having connected thereto a float 19. The larger portion of the valve 13 is so shaped in cross section as to provide a number of flat faces 20 for the purpose of allowing the fuel to pass by the valve and reach the inside of the bowl B. A light coiled expansion spring 21 is arranged behind the valve 13 for the purpose of merely assisting in closing the valve 13 in case the pressure of fuel in the bowl is not sufficient to fully elevate the float to the limit of its movement.

The operation of the mechanism just described is as follows: When the float 19 is at the upper limit of its movement, which is the case when the fuel is at its normal level in the bowl, the arm 16 moves away from the valve 13 and permits said valve to fully close and cut off further admission of fuel to the bowl. As the float 19 moves downwardly due to the falling of the level of fuel in the bowl, the arm 16 presses against the stem 15 and unseats the valve 13 thereby allowing more fuel to flow into the bowl B.

25 22 designates an overflow pipe which communicates with the bowl B at an elevation above the inlet valve 13 and below the discharge orifice of the nozzle or jet 11, so that the fuel may overflow before reaching the 30 height of the nozzle. The discharge end of the pipe 22 may be arranged at any place sufficiently remote from the carbureter to eliminate danger of fire due to backfire from the engine.

35 The air chamber C extends horizontally and is formed with an upstanding neck portion 23 which is fastened as shown at 24 to the lower end of the carbureting chamber A. The carbureting chamber is formed 40 preferably in the bottom thereof with the auxiliary air intake orifice 25 in conjunction with which co-operates an auxiliary air inlet valve 26 of the flap type, the same being mounted at one end upon a hinge pin or 45 rod 27 which extends through the opposite side walls of the air chamber as shown in Fig. 10 and is centered by means of washers or collars 28 to prevent the side edges of the valve from working in frictional contact 50 with the side walls of the air chamber. On its upper side the valve 26 is provided with a lug 29 to which is attached one extremity of a coiled expansion spring 30 the other extremity of which is attached to the free 55 end of an adjustable spring support 31 having oppositely extending pintles 32 which are journaled in bearings 33 fastened by the means 34 to the bottom wall of the air chamber as shown in Fig. 9.

60 One end of the air chamber C is closed by means of an end wall 35 shown in the form of a plug inserted in the end of the air chamber and secured by fastening means 36. A tensioning device 37 shown in the 65 form of a screw is threaded through an

opening in the end wall 35 so as to bear at its inner end against the adjustable spring support 31 for the purpose of compressing or relieving said spring to enable the valve 26 to open with greater or less ease. The 70 tensioning device 37 is preferably provided with a milled head 38 adapting it to be turned by hand and said head is shown as engaged by a spring detent 39 fastened at 40 to the end wall 35 of the air chamber. 75

In its upper side the air chamber is formed with another orifice 41 normally closed by means of a combined relief valve and gate 42 which is hinged at 43 to the air chamber. The working faces of the members 26 and 42 are preferably lined with suitable packing material as shown at 44 to obtain a tight closure of the orifices 25 and 41. A spring 45 is employed in connection with the relief valve 42 for holding the 80 same normally closed with a very light pressure which will not prevent the free opening of said valve and gate 42 in case of back fire thus allowing the exploding charge to escape from the air chamber without any 85 tendency of the same to enter the bowl B containing the liquid fuel.

At its other end the air chamber is formed with a main or primary air inlet orifice 46 normally closed by means of an air inlet 90 strangler valve 47 which is pivotally mounted at 48 on the air chamber and comprises an operating arm 49 to which any suitable connection may be attached. The valve 47 is normally open so as to afford the main air 100 supply but in starting an engine in cold weather, in order to obtain less air and therefore a richer mixture, the air valve 47 is closed so that the only supply of air is obtained through the orifice 25, the inrush 105 of air being resisted by the spring seated valve 26.

From the foregoing description, taken in connection with the accompanying drawings, it will now be understood that the carbureter comprises the three main sections or members A, B and C and that the air chamber and the mixing chamber are in direct communication with each other, while the fuel containing bowl is out of communication with both the air chamber and the mixing chamber excepting only through the small discharge orifice at the extremity of the nozzle or jet 11, therefore in case of back fire, the flame will be directed downwardly 110 through the mixing chamber and through the large orifice in the neck 23 into the air chamber C and thence outwardly through the relief valve 42. The flame is thus prevented from reaching the fuel in the bowl B. Furthermore, no carbureted air is retained in the bowl B as the same escapes through the safety vent tube 22 which may be led off to any desired point where the fuel laden air passing therethrough can not 115 120 125 130

be ignited by any flame or spark. The relief valve 42 relieves the pressure on the air valve 26 and is also useful in giving access to the spring 30 within the air chamber. The overflow pipe 22 is particularly valuable in case the inlet valve becomes leaky or in case any of the other mechanism controlled by the float becomes defective or inoperative for any reason, frequently resulting in the flooding of the carbureter and the ignition of the fuel within and exteriorly of the same in case of back fire.

Having thus described our invention, we claim:—

15 In a carbureter, the combination of a substantially vertical carbureting chamber of a tubular formation, a horizontally elongated air chamber at right angles to the bottom of said carbureting chamber projecting on opposite sides thereof and having an outlet of the cross sectional capacity of

the carbureting chamber, a fuel containing bowl arranged exteriorly of both the carbureting chamber and the air chamber, said bowl having an outlet nozzle discharging 25 upwardly within the carbureting chamber, said air chamber being formed with an air inlet orifice in the bottom thereof, an inwardly opening spring seated flap valve for said orifice, tensioning means for said valve, 30 a pressure relief opening in the top wall of said air chamber, a valve for the last named opening, and a strangler valve-controlled air inlet at one end of said air chamber.

In testimony whereof we affix our signatures in presence of two witnesses.
